UNITED STATES PATENT OFFICE.

HARRY GLENN WEEKS, OF PITTSFIELD, MASSACHUSETTS, ASSIGNOR TO GENERAL ELECTRIC COMPANY, A CORPORATION OF NEW YORK.

CONNECTOR FOR ELECTRIC CONDUCTORS.

945,995.

Specification of Letters Patent. Patented Jan. 11, 1910.

Application filed August 3, 1908. Serial No. 446,562.

To all whom it may concern:

Be it known that I, HARRY GLENN WEEKS, a citizen of the United States, residing at Pittsfield, in the county of Berkshire, State of Massachusetts, have invented certain new and useful Improvements in Connectors for Electric Conductors, of which the following is a specification.

This invention relates to means for connecting electrical conductors and has for its object the provision of a device of this character whereby the circuit connections may be quickly made and broken in a simple and efficient manner.

In the accompanying drawing, in which I have shown my invention embodied in concrete form, Figure 1 is an elevation partly in section of one member of my connector; Fig. 2 is an elevation of the other member; Fig. 3 is an end view of the device shown in Fig. 1; Fig. 4 is a similar view of the member shown in Fig. 2; and Figs. 5 and 6 show the two positions of my device with the circuit connections made in each case.

Referring to the drawing, 10 represents one member of my connector which may be called the plug member, and 11 represents the coöperating or socket member. These two members are adapted to be connected together in two positions so as to obtain two different arrangements of the circuits. In the device I have shown, the member 10 is the one which is usually fixed while member 11 is connected to the source of current and is shifted. The member 10 consists of a block of insulation in which are embedded the two single plug terminals 12 and 13 provided with binding screws 14 and 15 respectively. The third plug 16 is likewise mounted in the block of insulation in line with the other two so that the plug 13 is intermediate the other two. This plug is surrounded by a conducting sleeve 17 from which it is separated by an insulating sleeve 18. This sleeve is spaced from the plug 16 at its inner end so as to permit the socket to fit between the two parts. Binding screws 19 and 20 are arranged for making circuit connections to these two parts. The member 11 is a block of insulating material preferably made in halves as shown and held together by screws. This block of insulating material 55 is provided with three apertures 21, 22 and

23, all opening into a common aperture 24 through which the cord containing the electrical conductors is brought. In two of these apertures are placed socket terminals 25 and 26 connected with the conductors 27. The particular design of these terminals forms no part of my invention and need not, therefore, be described in detail. The socket portion simply consists of split tubes adapted to fit over the plug terminals, 60 so as to make a good electrical joint. The aperture for the socket 25 is enlarged at 28 so as to permit the sleeve 17 to pass over the socket while the plug 16 enters the socket. In this way the socket 25 makes electrical 65 connection with both the plug 16 and the sleeve 18. With this arrangement it will be seen that when the two parts 10 and 11 are connected, the plug 13 always enters the socket 26, but the plug 12 is adapted to 70 enter either the socket 25 or the aperture 21, while the plug 16 and sleeve 17 are likewise adapted to enter either of the apertures 21 or 23. This is accomplished by simply turning one of the other members, as for instance member 11, through 180°.

In Figs. 5 and 6 I have shown my device in connection with coils, which may be coils of a heater. In heating devices it is frequently desirable that the circuits be arranged so that two or more heats may be employed, and for purposes of illustration I have shown my connector with this type of device. In these figures R and R' represent the two heating coils, which are connected to the mains L and L'. In Fig. 5 the two parts 10 and 11 are placed together in the relative positions shown in Figs. 1 and 2, so that the resistances R and R' are connected in parallel. The current passes from the line L 85 to socket 25, plug 16, resistance R' and back to line through socket 26. Current at the same time passes from line L through socket 25, sleeve 17, conductor 29, resistance R and back to line L' through socket 26. By turning the member 11 through 180° the parts 90 will be in the position shown in Fig. 6, in which the current simply passes through the resistance R.

It will be seen that I have provided a very simple and efficient arrangement for connecting the circuits and varying their arrangement.

While I have shown my invention in connection with a special structure and as oper-

ating in a definite manner, it should be understood that I do not limit my invention thereto except in so far as it is limited by the scope of the claims annexed hereto.

5. What I claim as new and desire to secure by Letters Patent of the United States, is—

1. A connector for electric conductors comprising a member having two circuit terminals arranged for connection to a 10 source of current, and a coöperating member having three terminals, two of which are insulated from each other and simultaneously engage one of said coöperating terminals.

15. 2. A connector for electric conductors comprising a member having four terminals, two of which are adjacent and insulated from each other, and a coöperating member having two circuit terminals one of which 20 is arranged to engage either a single coöperating terminal or the two insulated terminals simultaneously.

25. 3. A connector for electric conductors comprising a member having two single terminals and a double terminal, and a coöperating member having two terminals one of which always engages one single terminal while the other engages either the other single terminal or the double terminal.

30. 4. A connector for electric conductors comprising a casing having three apertures, two of which contain circuit terminals, and a coöperating member having three terminals so arranged as to enter the apertures 35 and engage the two terminals.

35. 5. A connector for electric conductors comprising a casing having three apertures, two of which contain circuit terminals arranged for connection to a source of current,

and a coöperating member having three terminals, one of which is double and so arranged as to enter the apertures and engage the two terminals. 40

6. A connector for electric conductors comprising a member having a single terminal and a double terminal equally spaced on each side of a central terminal, and a coöperating member having two terminals one of which always engages the central terminal while the other engages either the single 50 terminal or the double terminal. 45

7. A connector for electric conductors comprising a casing having three apertures, two of which contain socket terminals arranged for connection to a source of current, 55 and a coöperating member having three plug terminals arranged to enter the apertures to engage the sockets, one of said plug terminals having an independent connecting portion insulated from the main terminal. 60

8. A connector for electric conductors comprising a casing having three aligned apertures, socket terminals within two adjacent apertures arranged for connection to a source of current, and a coöperating member having three plug terminals similarly arranged to enter the apertures and engage the sockets, one of the end plug terminals having an independent connecting portion insulated from the main portion to form two 65 parallel circuits. 70

In witness whereof, I have hereunto set my hand this 31st day of July, 1908.

HARRY GLENN WEEKS.
